DESIGN FOR A HOLDING PIN

Ben Elkins, Brooklyn, N. Y.

Application December 5, 1946, Serial No. 135,272

Term of patent 3½ years

(Cl. D54—9)

To all whom it may concern:

Be it known that I, Ben Elkins, a citizen of the United States, resident of the Borough of Brooklyn, in the county of Kings, city and State of New York, have invented a new, original, and ornamental Design for a Holding Pin, of which the following is a specification, reference being had to the accompanying drawing, forming part thereof.

I claim;

The ornamental design for a holding pin, substantially as shown.

BEN ELKINS.
